UNITED STATES PATENT OFFICE.

GUSTAVE LIDSEEN AND WALTER J. BEST, OF CHICAGO, ILLINOIS.

HAM BOILER.

Application filed July 3, 1926. Serial No. 120,295.

This invention relates to a ham boiler or the like and concerns itself primarily with the superstructure which is designed to maintain the ham under pressure.

5 It is an object of this invention to provide such a superstructure in which the compression springs that act on the pressure head may be compressed without the aid of an extra pressure applying device before the 10 superstructure is applied to the boiler, and in which the compression of the springs can be slightly relieved for independent action after the superstructure has been applied.

15 The invention comprises the novel structure and combinations hereinafter described and more particularly pointed out and defined in the appended claims.

20 In the accompanying drawings which illustrate a preferred embodiment of this invention and in which similar reference numerals refer to similar features in the different views:

25 Figure 1 is a vertical sectional view of the apparatus taken upon the line I—I of Figure 2.

Figure 2 is a top plan view of the apparatus.

30 Figure 3 is a transverse sectional view of the device taken substantially upon the line III—III of Figure 2.

Figure 4 is a fragmentary detail view illustrating a modified manner of attaching the superstructure to the boiler proper.

35 Figure 5 is a sectional view upon the line V—V of Figure 4.

As shown on the drawings:

40 As illustrative of this invention, there is shown a receptacle 1 which constitutes the boiler proper. Suitable ratchet bars 2 are attached upon the ends of the boiler. The superstructure of the boiler comprises a pressure-head 3 having a downwardly turned margin. Spaced standards 4 rise from the pressure head. Each standard consists of a 45 pair of contiguous flat bars provided with attaching flanges or lugs 5 riveted to the pressure head. The superstructure further comprises a channel like anchoring member 6 having pawls 7 pivoted thereto for engaging the ratchet bars 2. The pawls 7 have a ratchet engaging hook 8 upon their lower ends for co-action with the teeth of the ratchet bars 2. The hooks 8 are bevelled 50 upon their outer surfaces for readily slipping past the teeth of the bar.

A modified form of ratchet mechanism is shown in Figure 4. In this form a suitable bar 9 is pivoted at each end of the channel member 6. A pawl 10 is pivoted upon the lower end of the bar 9 for engaging a ratchet bar 11 which constitutes the outer wall of a casing 12 attached to the end of the boiler 1, the casing 12 forming a pocket or sheath into which the bar 9 extends. The anchoring member 6 is provided with suitable slots for slidably receiving the standards 4 which are connected to the channel member by toggle mechanism. Each toggle mechanism comprises a pair of parallel links 13 which are anchored at their lower ends to a pair of angle clips 14 on the member 6 by a bolt or rivet 15, the shank of which passes thru an elongated slot 16 (Figure 1) in the standard 4. Each slot 16 has an arcuate entrance at its upper end and a notch 17 in the rear wall 75 in arcuate alinement with said entrance.

The upper ends of each pair of links 13 are connected to the ends of a pair of angular operating members or arms 18 by pivot pins 19 which are so located as to oscillate upon the radius of the arcuate entrance to the slots 16. Each pair of arms 18 is pivoted to a standard 4 by a pivot pin 20 which is also the center of the arcuate entrance to the slot in such standard. A link 21 connects the upper ends of the angular arms 18. One pair of arms 18 is extended beyond its pivot point and a sheath 22 is attached to such extended ends for receiving an operating handle or lever. 80

45 A coiled compression spring 23 surrounds each standard 4. These springs are confined between the pressure head 3 and the channel member 6 which forms a partial housing therefor. Obviously, when the channel member 6 is anchored to the boiler and the pressure head 3 is pressing on a ham, the springs if released from locked position will exert a resilient force upon the pressure head. 95

50 In using this apparatus, the superstructure is removed, a ham is placed in the boiler, the lever in the sheath 22 is pressed downwardly for swinging the pivots 19 into the notches 17 which is at a point beyond dead center whereby a locking action is secured between the parts. As the pivots 19 are thuswise moved inwardly and the toggle is straightened, the pressure head 3 and channel member 6 will move relatively toward each other 105 110

for compressing the springs 23. In the past, a separate device was used to compress the springs. This invention obviously eliminates such a device.

5 When the springs have been compressed and locked in compressed position by the toggles mechanism swinging beyond dead center, the superstructure is applied to the boiler; the pawls 7 being engaged with the 10 ratchet bars. Of course, the superstructure will be manually pressed upon the ham. When the superstructure has been thuswise secured, the lever in the sheath 22 will be elevated for breaking the toggles as shown in 15 Figure 1, whereby the compressed springs 23 will be released for acting on the pressure head while the ham is being boiled.

From the foregoing it will be appreciated that in the device involving this invention, 20 no extra pressure device is required to compress the springs, since it is only necessary to operate the lever in the superstructure to do so. Consequently, not only is a great deal of time and labor saved, but also the cost and 25 expense of extra pressing mechanism is eliminated.

We are aware that many changes may be made, and numerous details of construction may be varied through a wide range without 30 departing from the principles of this invention, and we therefore do not purpose limiting the patent granted hereon, otherwise than necessitated by the prior art.

We claim as our invention:

35 1. In a ham boiler, a super-structure comprising a pair of relatively movable members, yielding means between said members, and a connection between said members comprising a swingable element operable for compressing said yielding means and simultaneously locking said members against relative movement.

2. In an apparatus of the class described, a super-structure comprising a pair of relatively movable members, yielding means between said members, a connection between said members comprising a swingable element operable for compressing said yielding means and locking said members against relative movement, said element being operable by a swinging movement for releasing said members for relative movement.

3. In an apparatus of the class described, a super-structure comprising a pair of relatively movable members, a pair of connections between said members, yielding means between said members, and means for simultaneously operating said connections for causing relative movement of said members.

60 4. In an apparatus of the class described, a super-structure comprising a pair of relatively movable members, yielding means between said members, a pair of connections between said members, means for simultaneously operating said connections for locking said members against relative movement.

65 5. In an apparatus of the class described, a super-structure comprising a pressure head and an anchoring member, toggle mechanism connecting said head and member, resilient means between said head and member, and means for actuating said toggle mechanism for compressing said resilient means and locking the same in compressed position.

70 6. In an apparatus of the class described, a super-structure comprising an anchoring member, a pressure-head and a pair of toggles connecting said member and head, yielding means between said member and head, and means for simultaneously actuating said toggles for drawing said head and member toward each other and compressing said yielding means, said toggles being swingable beyond dead center for locking 75 said yielding means in compressed form.

80 7. In an apparatus of the class described, a super-structure comprising an anchoring member, and a pressure-head having standards projecting through said anchoring member, yielding means between said head and member, a pair of toggles connecting said standards and anchoring member, said standards having slots open at their upper ends for guiding said toggles, and means for 85 simultaneously operating said toggles.

90 8. In an apparatus of the class described, a super-structure comprising an anchoring member, a pressure-head having standards projecting through said member, yielding means between said head and member, said standards having slotted portions, a pair of toggles connecting said anchoring member and standards, each toggle having a pivot pin extending through the slot in its adjacent standard, and means for simultaneously 95 actuating said toggles.

100 9. In an apparatus of the class described, a super-structure comprising an anchoring member, a pressure-head having standards extending through said anchoring member, yielding means between said head and member, each standard having a slot provided with an arcuate way, a toggle connecting each standard with the anchoring member, each toggle having a pivot pin extending through said slot, and means for simultaneously 105 actuating said toggles.

110 10. In a ham boiler, an anchoring member, a pressure-head, yielding means between said head and member, toggle connections between said head and member, means for guiding the movements of said toggles, and means for simultaneously operating the same.

In testimony whereof we have hereunto subscribed our names.

GUSTAVE LIDSEEN.
WALTER J. BEST.
